UNITED STATES PATENT OFFICE.

CHRIS A. CHRISTIANSON, OF ULEN, MINNESOTA.

VENTILATING SASH.

Application filed November 11, 1927. Serial No. 232,625.

My invention relates to new and useful improvements in ventilating sashes, and the same is adapted in association with the conventional rain shield employed in connection 5 with the window frame at the interior of a building.

The purpose of my novel ventilating sash is to provide means whereby a normally 10 tilttable and removable window sash frame may be released from its position as a part of the window to be supported against the connecting wall of a conventional window rain shield.

The main object of the invention is to provide 15 a ventilating sash, the sash portion of which is normally tilttable, and which may be gradually released from its normal position to a tilted position against the connecting wall of a conventional window rain shield.

Another object resides in intentionally 20 maintaining the sash in a tilted position whereby the same will be prevented from being jarred or otherwise disturbed, probably resulting in the breakage of the panes 25 thereof.

A further object resides in providing a construction in association with the rain shield, whereby the sash may be supported in an elevated position to further protect the interior 30 of the building from the entrance of rain, while at the same time allowing for the proper ventilating of the room.

Another object resides in providing tensional means whereby the elevated sash will 35 be maintained against displacement.

Other various novel objects and advantages of my improved ventilating sash will 40 become apparent as the same is better understood from the specification and claims to follow.

In the drawings:—

Figure 1 represents a vertical sectional view through a conventional window rain shield disclosing one of the tensional devices 45 secured on the top edge of one of the side walls thereof.

Figure 2 represents a fragmentary plan view of one end wall of the conventional rain shield, the same disclosing the tensional 50 means engageable against the sash.

Figure 3 is a fragmentary sectional view taken substantially on line 3—3 of Figure 2, and

Figure 4 is a perspective view of the 55 bracket member employed for supporting the tensional device.

Now for a more detailed description of my invention I refer to the drawing in which like numerals designate like parts.

For convenience in properly illustrating 60 the manner in which my improved ventilating sash is mounted, I represent in the drawing the sill A of the usual window frame construction. The conventional window rain shield includes side walls B, and the connecting wall C.

In carrying out my invention, I provide a jamb board 1, preferably having its ends connected to the respective vertical frame of the conventional window frame. The 70 same is adapted to be positioned in a horizontal plane, and substantially coplanar with the top edge of the connecting wall C. The jamb board is provided with the jamb face 2 against which the upper edge portion 75 of the sash 3 is adapted to bear. The lower edge of the sash is transversely beveled at 4 so as to fit flatly upon the inclined surface of the sill A. The sash is positioned in a manner whereby when the tensional 80 means which will be hereinafter fully described is released from engagement with the top inner side of the sash, the said sash will tilt inwardly.

A stop strip 5 is secured to each side wall 85 of the rain shield, so that the one longitudinal edge thereof will bear against the connecting wall C thereof, in a manner clearly shown in Figure 1. The strip is preferably tapered throughout its length, and is enlarged at 6 to provide a base portion against 90 the inclined outer edge of which the sash 3 is adapted to rest when in tilted position. At the upper end of this base portion a shoulder 7 is provided, at the outer end of 95 which an upstanding lug 8 is formed.

The bottom edge of the sash is to be supported upon the shoulder 7 of the respective base portion, when the sash is in elevated position.

I provide a pair of tensional devices generally referred to by the numeral 9, each of which is adapted to be supported upon the respective side walls of the rain shield. In supporting the respective tensional devices, I 100 provide a bracket 10, having a pair of depending apertured lugs 11—11, by which the same is secured to the top edge of the side wall. These lug members are formed at each end of one longitudinal edge of the 105 bracket, while the intermediate portion thereof is formed with an upstanding flange 110

12. The opposite longitudinal edge is provided with an upstanding flange 13, both of which flanges are formed with horizontally registering openings 14. Additional securing means 15 may be employed for securing the bracket more securely to the top edge of the side wall. A bushing 16 extends through the respective openings 14 and is adapted to project a substantial distance beyond the outer side of the respective flanges 12 and 13. The coiled spring 17 is convoluted about the bushing and disposed between the respective upstanding flanges of the brackets, in a manner whereby one end portion thereof is secured within the opening in the upstanding flange 12 at 18. The opposite end of the spring is fixed to the bushing.

An elongated arm 19 is formed with an opening adjacent one end thereof, and through which a bolt 20 extends. This bolt 20 projects through the bushing and for a substantial distance beyond the opposite end thereof. Suitable washers 21-21 are interposed between the head of the bolt and one side of the arm, and between the opposite side of the arm against the end of the bushing. The projecting end portion of the bolt has keyed thereon the pulley wheel 22, while the nut 23 threaded on the threaded end of the bolt is adapted to tightly engage the wheel against the end of the bushing. Suitable washers may be interposed between the nut and the pulley wheel, and between the opposite side of the pulley and the adjacent end of the bushing. A flexible strand member 24 is connected in the channel portion of the pulley wheel in a manner clearly shown in Figure 2 whereby a pull on the strand will cause the rotation of the bushing, and the consequent movement of the arm 19.

An extension 25 of substantially U-shape cross section is formed with an elongated longitudinally extending slot 26, through which a bolt extends for securing said extension to the free end of the arm 19. The inner end portion of the extension is adapted to engage the under side of the arm whereby the extension will be maintained rigidly with the arm when the same is in engaged position with the jamb board, as is shown in Figure 1. The outer end of the extension is bifurcated between the furcations of which the roller 27 is rotatably mounted. This roller is adapted to engage the inner upper portion 55 of the sash when the same is in its normal upright position.

It will be seen that when it is desired to release the sash 3 to provide ventilation for the room, the flexible strand 24 is pulled, whereby the pulley wheel 22 will cause the rotation of the bushing 16, and the consequent lowering of the arm 19. This action is against the tension of the spring 17, and in this manner the sash may be gradually lowered to the dotted line position as shown

in Figure 1. The rotation of the bushing is continued until the connection between the extension 25 and the arm 19 has been broken in passing over the top edge of the connecting wall C.

When the roller 27 has passed over the top edge thereof, the strand 24 may thence be released, which will allow the extension 25 to bear tensionally against the top edge of the sash. In this position, the sash is prevented from becoming displaced due to this tension engagement of the extension.

When it is desired to elevate the sash in order to prevent any entrance of rain within the room, the sash is lifted to the position represented in the drawings by dotted line construction. The bottom of the sash is then supported upon the respective shoulders 7 of the base portion 6 and the roller 27 will continue to engage the sash at the now outer side thereof.

It will be seen that I have provided a very novel ventilating sash, which may be tilted from its normal position to allow for the thorough ventilation of the room. However, in exceedingly bad weather, the same may be elevated to a higher position, whereby rain will be entirely prevented from entering the room. In each instance the tensional device I have provided will engage the sash so as to prevent any liability that the same will become displaced and damaged.

Having thus described the invention, what I claim as new and desire to secure by Letters Patent is:—

1. In a ventilating sash in association with the usual window frame and a conventional window rain shield, a jamb board secured to the window frame, a tilttable sash adapted to have its upper edge portion bear against the board, the lower edge of the sash to be supported upon the window sill, a pair of tapering rest strips secured to the side walls of the rain shield and against which the sash is adapted to rest when in tilted position, and tensional means for maintaining the sash rigidly in tilted position.

2. In a ventilating sash in association with the usual window frame and the conventional window rain shield, a jamb board secured to the window frame, a tilttable sash adapted to have its upper edge portion bear against the board, the lower edge of the sash to be supported upon the window sill, a pair of tapering rest strips on the side walls of the rain shield and against which the sash is adapted to rest in tilted position, a shoulder at the lower portion of each rest strip upon which the sash may be supported in elevated position, and tensional means for maintaining the same securely in position.

3. In a ventilating sash in association with the usual window frame and the conventional window rain shield, a jamb board

secured to the window frame, a tilttable sash adapted to have its upper edge portion bear against the board, the lower edge of the sash to be supported upon the window sill, a pair of tapering rest strips on the side walls of the rain shield and against which the sash is adapted to rest in tilted position, a shoulder at the lower portion of the rest strip upon which said sash may be supported in elevated position, and tensional means for maintaining the same securely in position, said tensional means including a bracket supported on one of said side walls, a stub shaft rotatably mounted on said bracket, an arm projecting laterally from one end of said shaft, and a spring on said shaft for tensionally maintaining the arm against the tilttable sash.

4. In a ventilating sash in association with the usual window frame and the conventional window rain shield, a jamb board secured to the window frame, a tilttable sash adapted to have its upper edge portion bear against the board, the lower edge of the sash 25 to be supported upon the window sill, a pair of tapering rest strips on the side walls of the rain shield and against which the sash is adapted to rest in tilted position, a shoulder at the lower portion of the rest strip upon 30 which said sash may be supported in elevated position, and tensional means for maintaining the same securely in position, said tensional means including a bracket supported on one of said side walls, a stub shaft rotatably mounted on said bracket, an arm pro-

jecting laterally from one end of said shaft, and a spring on said shaft for tensionally maintaining the arm against the tilttable sash, and means for disengaging said tensional arm.

5. In a ventilating sash in association with the usual window frame and the conventional window rain shield, a jamb board secured to the window frame, a tilttable sash adapted to have its upper edge portion bear against the board, the lower edge of the sash to be supported upon the window sill, a pair of tapering rest strips on the side walls of the rain shield and against which the sash is adapted to rest in tilted position, a shoulder at the lower portion of the rest strip upon which said sash may be supported in elevated position, and tensional means for maintaining the same securely in position, said tensional means including a bracket supported on one of said side walls, a stub shaft rotatably mounted on said bracket, an arm projecting laterally from one end of said shaft, and a spring on said shaft for tensionally maintaining the arm against the tilttable sash, and means for disengaging said tensional arm, said latter means including a pulley carried at the opposite end of the shaft, and a flexible element having a portion thereof wound around the pulley by the tension of the spring, said elements being adapted to be pulled for swinging the arm from engagement with the sash.

In testimony whereof I affix my signature.
CHRIS A. CHRISTIANSON.
